MECHANISM FOR DRYING THE PAPER IN
PRINTING PRESSESGustave A. Friess, Rye, N. Y., assignor to News
Syndicate Co. Inc., New York, N. Y., a corpo-
ration of New York

Application August 3, 1935, Serial No. 34,561

2 Claims. (Cl. 34—48)

My invention relates to a new and improved method of and new and improved mechanism for drying the paper in a printing press.

One of the objects of my invention is to dry the paper, after the paper has been printed, so as to effectively remove the solvent which is an ingredient of the printing ink.

Another object of my invention is to provide a simple and convenient method and apparatus whereby the fumes or vapors of the solvent will be effectively withdrawn from the room in which the printing is taking place, thus diminishing fire hazard, and also diminishing the hazard to the health of the workmen.

Another object of my invention is to provide a method and mechanism whereby air, either heated or unheated, is caused to move in the form of a current along the paper, subsequent to the printing of the paper, and this air current is then drawn into an exhaust chamber or compartment, the air then being discharged into any suitable outlet.

Another object of my invention is to provide a device of this kind which can be readily installed in connection with a standard printing press, and in which the essential parts of the mechanism can be moved so as to permit access to the essential parts of the printing press.

Other objects of my invention will be set forth in the following description and drawings, which illustrate a preferred embodiment thereof, it being understood that the above general statement of the objects of my invention is intended generally to illustrate the same, but without limiting it in any manner.

Fig. 1 is a front elevation showing one form of apparatus which can be used for the purposes of my invention.

Fig. 2 is a side elevation of Fig. 1, taken at the left-hand side of Fig. 1.

Fig. 3 is an elevation taken at the inner side of the hood which forms one of the elements of the invention.

Fig. 4 is a side elevation showing the right-hand side of Fig. 3.

Fig. 5 is an elevation taken at the left-hand side of Fig. 3.

Referring to Fig. 1 and Fig. 2, the device is provided with a blower B, or any other suitable device for producing a current of air.

The blower or fan B is operated by means of a motor 8.

As indicated by the arrow at the left hand side of Fig. 2, the air is drawn inwardly into the casing of the blower B, through a compartment or

chamber 7, which serves as an inlet for the casing of the blower B. The intake end of said member 7 can be provided with a wire screen or the like.

The air is forced downwardly through the casing 10, which communicates at its bottom with branch casings 10a and 10b.

As shown at the left hand side of Fig. 1, the branch casing 10a communicates with a pipe 11, and this pipe 11 communicates with the compartment 26 of a horizontal pipe 12. As shown in Fig. 4 and in Fig. 5, the pipe 12 is divided by means of a partition 25, into compartments 26 and 26a.

This partition 25 is imperforate.

The compartment or chamber 26 of the pipe 12, communicates with a compartment or chamber 19a of a hood H. Said compartment 19a is provided with a series of outlets 14, at the upper end of the hood H. In this particular embodiment I have shown four outlets 14, but I can provide any desired number of said outlets.

As shown in Fig. 3, angle irons 6 are provided between the respective openings 14, and also at the left-hand end of the left-hand opening 14, 25 and also at the right-hand end of the right-hand opening 14.

The purpose of these angle irons 6 is to divide the inner face of the hood H into a series of sections. These angle irons 6 are removable.

If, for example, the web of paper has the full width of the hood H, all of said openings 14 can be opened. If, however, the web of paper has a width which is less than the entire width of the hood H, one or more of said openings 14 can be closed.

The discharge openings 14 are controlled by means of shutters 15. The shutters 15 for each discharge opening 14 can be adjusted individually, by means of manually operated handles 15a.

I have not shown the specific mechanism whereby the shutters 15 can be operated by turning the handle 15a, as any suitable conventional connecting mechanism may be provided.

Hence I can completely close any of the openings 14, or I can control the amount of air which is discharged from any said opening 14, by operating the shutters 15.

The air which is thus discharged at the upper end of the hood H, is directed downwardly and said air sweeps downwardly in the form of a downwardly directed current, along the inner face of said hood H.

At the bottom of said hood H a series of inlet openings 16 are provided. Said openings 16 may

be provided with louvres or shutters 17, and said shutters 17 may be either fixed or adjustable.

The hood H is hollow, and it is provided with a longitudinal partition 18, so that the inlet openings 16 communicate only with the compartment 19, which is separated from the compartment 19a by the imperforate partition 18. Hence the air which is forced through compartment 26, is forced out of openings 14, since compartment 10 19a is closed, save at its upper end.

The upper end of the compartment or chamber 19 communicates with the discharge compartment 26a of the pipe 12. The intake openings 16 are located at the lower end of compartment 15 19.

The outlet compartment 26a communicates with an outlet pipe 20, which corresponds generally to the pipe 11 which has previously been mentioned. The pipe 20 is connected by means 20 of the pipe 21, to a casing 60, and air is exhausted from said casing 60 by means of a suction fan Ba, which is operated by means of a motor 24. The air is thus discharged through a suitable outlet pipe 23, which can be located 25 outside of the building or connected to any suitable chamber for discharging the exhausted fumes and vapors.

The web W of the paper which is to be printed, is led between the printing members 1 and 3. 30 The roller 3 may be an engraved roller, if the paper is to be printed by means of the gravure process. The roller 1 is the usual impression roller, having an outer sleeve made of resilient rubber or the like. Pressure is supplied by means of 35 the usual roll 2.

The freshly printed web of paper is therefore led upwardly adjacent the inner face of the hood H. For this purpose, the web of paper is guided by means of a series of idler rollers 4, which 40 are mounted in a frame 30. As shown in Fig. 1, the frame 30 in which the rollers 4 are mounted, is connected to the frame F of the machine, by means of brackets 41.

Fig. 1 shows one of said idler rollers 4, and it 45 can be noted that the length of each roller 4 is approximately equal to the width of the hood H.

The inner face of the hood H is provided with 50 projections 61, which fit in corresponding grooves in the frame 30, so that any side leakage of the air is prevented.

As the freshly-printed web of paper is led upwardly along and adjacent to the hood H, the 55 wet ink on the paper is dried by the downwardly moving current of air.

The drying action results in rapid vaporization of the solvent which has been used in the 60 ink. Since the air is drawn into the lower end of the hood H, through the inlet openings 16, the fumes or vapors are drawn directly into the compartment 19, so that said fumes can be discharged through the pipe 21.

The web of paper is also led around a roller 5, which may be heated. Hence, and as shown in Fig. 2, the web of paper is heated in a zone 65 which is spaced from the zone of printing. The air current moves in a direction away from the zone of heating and towards the zone of printing, and in a direction which is counter to the direction of movement of the freshly printed web.

Before the web of paper is withdrawn from 70 the printing press, and after it has passed over the heated roller 5, the web may be moved downwardly along the inner face of a hood Ha, which corresponds in every respect to the hood H, save 75 that the hood Ha is shorter than the hood H.

The branch casing 10b communicates with the inlet compartment of the hood Ha, by means identical with those which have previously been described.

Likewise, the outlet or exhaust compartment 5 of the hood Ha, communicates with the exhaust casing 60, by means of any suitable connection.

This connection may be similar to the branch casing 10b.

For convenience in using the machine, the 10 hoods H and Ha may be swung outwardly.

As shown in Fig. 1, a manually operated handle 32 operates one of a pair of meshing bevel-gears 33. These gears turn a shaft 34, and this operates one of a pair of meshing bevel-gears 35, thus 15 operating a horizontal shaft upon which the gear 36 is mounted. The gear 36 meshes with another gear 37 (see Fig. 2), and this gear 37 meshes with a segment 38, which is mounted upon a shaft 50.

Said shaft 50 has another member mounted thereon, this other member being similar to the member 38, but without the teeth.

The segment 38 has a rod 39 pivotally connected thereto, and said rod 39 is pivotally connected 25 to the hood Ha.

The segment 38 also has a rod 40 pivotally connected thereto, and said rod 40 is pivotally connected to the hood H.

The other member which is mounted upon the 30 shaft 50 has similar rods, so that connecting means are provided at each end face of the hood H and of the hood Ha.

By turning the handle 32, the hoods H and Ha can therefore be simultaneously turned in 35 opposite directions, and away from the means for guiding the web of paper.

In order to permit this turning movement of the hoods H and Ha, the said hoods are connected to the pipes 11 and 20 which are located 40 at their upper ends, so that said hoods turn in unison with said pipes.

The pipes 11, 12 and 20 may be connected so 45 that they turn in unison with the hoods H and Ha, suitable bearings being provided.

The web of paper is thus dried by one or more counter-currents of air, each current being forced out of the outlet or outlets of a hood, and being forced into the inlet or inlets of the hood. Each hood has its outlets and inlets located at its inner face. The exhaust means Ba draw the air 50 into the hood. The suction fan Ba has a greater capacity than the pressure fan B. That is, during the operation of the device, the suction fan Ba can take in more air than is delivered by the pressure fan B. Hence some air is drawn upwardly along the inner surface of the hood, in addition to the air supplied by the current which is delivered by pressure fan B. This insures the effective removal of the vapors from the printing cylinder 3, and from that portion of the web 55 between said cylinder and the bottom of hood H. The hood H may be of any desired length, and its lower end may extend to the level of cylinder 3, or to any desired distance below the top 60 of said cylinder 3. The arrow in Fig. 2, shows how the vapors are removed. The air is exhausted away from the web in substantially a single zone which corresponds to the inlet openings 16 so that the air current has a sufficiently 65 long sweep along the freshly printed surface of the web, between the openings 14 and 16.

It will be noted that the web of paper is moved through an open space while it is being dried, as distinguished from the drying of objects in 70 75

a chamber which is tightly closed save for an inlet opening and an outlet opening.

The air current is confined between the web of paper, the inner face of the hood and the lateral projections 61. The exhaust effect is so powerful as to prevent any substantial escape of the vaporized solvent vapor into the press room. Many of the details shown herein may be omitted or varied without departing from the invention.

For example, I do not wish to be limited to any specific guide means for leaving the web of paper in substantially planar form, while the solvent is being removed from the ink. I have shown a preferred embodiment of my invention but it is clear that numerous changes and omissions can be made without departing from its spirit.

I claim:—

1. A method of drying a printed web of paper while moving said web of paper, which consists in directing a counter current of air along the printed surface of the web of paper, then heating the web of paper at the rear surface of the

paper by direct conduction from a heated member and then subjecting the printed surface of the heated paper to a second current of air, moving in the same direction as the paper, while substantially preventing any escape of the air 5 which is forced along the printed side of the paper.

2. In combination with means for printing a web of paper, a heated roller spaced from said printing means and adapted to contact with the 10 rear surface of the web of paper after said web has been printed upon, a hood located upon each side of said roller, each hood having an outlet and an inlet at its inner surface, and means for causing a current of air to move out of said 15 outlets and into said inlets, the outlet and inlet of each hood being vertically spaced from each other, the inlets being below said heated roller, and means for substantially preventing any lateral escape of the air. 20
